BOILER CLEANER

Louis F. Cooling, Chicago, Ill., and Samuel F. Cox, Detroit, Mich., assignors to Diamond Power Specialty Corporation, Detroit, Mich., a corporation of Michigan

Application May 19, 1930. Serial No. 453,758

4 Claims. (Cl. 122—392)

This invention relates to boiler cleaners and has particular reference to a boiler cleaner of the character in which a blower element is adapted to direct jets of cleaning fluid adjacent portions of the boiler to be cleaned.

One of the objects of this invention is to provide an improved form of bearing bracket for the blower element whereby the blower element may be supported adjacent the portions of the boiler to be cleaned.

The invention further contemplates the provision of a bearing bracket formed of separable sections whereby upon disassembly of the bearing bracket the blower element may be easily removed for the purposes of repair or replacement.

Other objects and advantages of the invention, together with the numerous novel details of construction thereof, will become more apparent as the following description proceeds, particularly when reference is had to the accompanying drawing wherein:

Figure 1 is an elevational view partly in section showing the mounting of a boiler cleaner in a boiler setting.

Figure 2 is a sectional view taken substantially on the line 2—2 of Figure 1.

Figure 3 is a sectional view taken substantially on the line 3—3 of Figure 2.

Figure 4 is a detail elevational view of a portion of the structure shown in Figure 2; and

Figure 5 is an end elevational view of the structure shown in Figure 4.

In practice it has been found that the most satisfactory way to support a blower element of a boiler cleaner adjacent the surfaces of the boiler to be cleaned is to weld a bearing bracket for the blower element to the adjacent boiler surfaces. By fixing the bearing bracket to the boiler surfaces or the like, the bearing bracket is

prevented from movement regardless of the inclination of the boiler surfaces and the blower element is thus maintained in fixed relation to the surfaces to be cleaned. It frequently happens, however, that a bearing bracket welded entirely to the boiler surfaces cannot be used because the space between boilers is not sufficient to permit an axial withdrawing of the blower element from the bearing brackets. The present invention therefore contemplates the provision

of a bearing bracket which includes a portion welded or otherwise fixed to the boiler part and a second portion detachably connected to the first portion so that the bearing bracket may be disassembled to permit a removal of the blower element from the bearing bracket by a lateral

rather than an axial movement of the blower element.

Referring then particularly to the drawing wherein like reference characters designate corresponding parts throughout all views, there is shown in Figure 1 a boiler cleaner mounted in a boiler setting in a position to discharge cleaning fluid adjacent the portions of the boiler to be cleaned. In this figure the reference character 10 designates a boiler wall provided with an opening 11 through which a blower element 12 extends. This blower element is provided with discharge nozzles 13 adapted to direct jets of cleaning fluid adjacent portions of the boiler to be cleaned, such, for example, as the boiler tubes 14.

Exteriorly of the boiler wall the blower element is rotatably journaled in a blower head designated generally by the reference character 15. This head includes a gooseneck 16 forming a connection between the cleaning fluid supply pipe 17 and the blower element and a suitable actuating mechanism for rotating the blower element which includes a gear 18 fixed to the blower element, this gear being engaged by a pinion 19 rotatable with a sheave wheel 20. A valve 21 is preferably provided for controlling the flow of cleaning fluid from the supply pipe to the blower element and this valve is actuated in timed relation to the rotation of the blower element by means of a lever 22 which is engaged by a cam 23 rotatable with the blower element. The structure of the blower head and the actuating mechanism for the blower element and valve form no part of this invention and are disclosed merely for the purpose of illustrating the manner in which the blower element is supplied with cleaning fluid and is rotated for directing the jets of cleaning fluid adjacent the portions of the boiler to be cleaned.

As illustrated, the blower element extends adjacent the portions of the boiler to be cleaned, such, for example, as the boiler tubes 14, and to provide means for supporting the blower element from these tubes, suitable bearing brackets designated generally by the reference character 25 are provided. By reference to Figure 1 of the drawing, it will be noted that the bearing brackets are shown as secured to the boiler tubes 14, but it is to be clearly understood that the bearing brackets may be secured to any portion of the boiler adjacent which the blower element extends.

Each bearing bracket includes a loop member 26 provided with the end portions 27, each of which is formed with an opening 28. The loop member is curved, as clearly illustrated in Figure

2 of the drawing, to embrace the blower element 12 and to constitute a bearing for the same.

Each bearing also includes a pair of lugs or anchor members 29 and each lug comprises a plate-like member provided with an aperture 30 and provided with a lower edge 31 which is formed on its ends with the bearing portions 32 curved, as clearly illustrated in Figure 5 of the drawing, to seat on the boiler tube 14. Intermediate the bearing portions 32, the edge 31 is beveled as indicated at 33 to facilitate welding of this portion of each lug to the boiler tube.

In assembling the bearing bracket, the lugs 27 may be set up on the boiler tube, the spaced bearing portions 32 providing means for holding the lugs in correct position. The lugs are then welded to the boiler tube as indicated at 34, the beveled portions of the lugs facilitating a thorough bonding of the lugs to the tube. With the lugs 20 fixed to the boiler tube the correct distance apart, the loop member 26 is detachably secured to the lugs by bolts 35 which pass through the openings 28 and 30 in the loop member and lugs respectively, these bolts being held in position by the nuts 36. Thus, the loop member is detachably secured to the lugs 29 and these lugs are in turn fixed to the boiler tube or boiler part by welding.

From the above it is believed that the structure and operation of the invention will be clearly apparent. The loop members, detachably secured to the lugs which in turn are fixed to the boiler part, constitute bearing brackets for supporting the blower element adjacent the parts of the boiler to be cleaned. Whenever it is desired to remove the blower element for the purpose of replacement or repair, the bolts 35 may be removed and the loop member detached from the lugs, permitting movement of the blower element out of the loop member. Thus, the invention provides means for supporting the blower element adjacent the surfaces of the boiler to be cleaned while permitting ready removal of the blower element by a disassembly of the bearing bracket. By the term "boiler surfaces", as used herein, is meant the heat transfer surfaces of the boiler. The heat transfer surfaces, as is understood, are those surfaces which are contacted by the heating fluid, and which absorb heat therefrom for transmission to a second fluid to be heated.

50 While the boiler tubes in Figure 1 are shown as being horizontally arranged with the bearing brackets above the tubes, it is to be clearly understood that the bearing brackets may, if desired, be fixed to the under sides of the boiler tubes, in which event the blower element will be suspended from the boiler tubes. Further, the boiler tubes may be inclined, as is customary in certain types of boilers, in which event the bearing brackets will be arranged at an angle to the horizontal. In every case, however, the bearing brackets will be prevented from movement relative to the boiler tubes regardless of the angle of inclination of the boiler tubes so that the blower elements will be supported at fixed points with reference to the portions of the boiler to be cleaned.

While the invention has been described with

considerable detail, it is to be clearly understood that the description is for the purpose of illustration only and is not definitive of the limits of the inventive idea. The right is therefore reserved to make such changes in the details of construction and arrangement of parts as will fall within the purview of the attached claims. For the sake of convenience, the invention has been described as being embodied in a bearing for supporting a boiler cleaner within a boiler. It will be apparent, however, that the inventive principles disclosed may be utilized for supporting a cleaner in any similar type of apparatus, and it is to be, therefore, understood that the term "boiler" wherever used in the specification or claims is to be construed as meaning a heat transfer apparatus or fluid heater of any character, while the term "boiler cleaner" is to be construed as meaning a cleaner for any such apparatus.

What we claim as our invention is:

1. The combination with a boiler surface and a blower element adjacent said surface of means to support the blower element from the boiler surface comprising two separate lugs, each lug being positioned and welded to said surface on opposite sides of said blower element, and a loop member detachably fastened to said lugs and partially surrounding said blower element.

2. The combination with a boiler surface and a blower element adjacent said surface, of means for supporting the blower element from the boiler surface and for restraining the blower element from movement in all directions with respect to said surface comprising two separate members, each member being positioned and welded to the boiler surface on opposite sides of the blower element and a U-shaped member detachably secured to said members and cooperating with the boiler surface to completely surround the blower element.

3. The combination with a boiler tube and a blower element extending transversely of said boiler tube, of means extending longitudinally of said tube, for supporting said element therefrom and for restraining said element from movement in all directions with respect thereto, said means comprising three separate members, two of which are positioned and welded to the boiler tube on opposite sides of the blower element and the third of which partially surrounds the blower element and is detachably secured to said welded members.

4. The combination with a boiler tube and a blower element adjacent said tube, of means for restraining said blower element from movement with respect to said tube comprising two separate lugs, each lug being positioned and welded to said boiler tube on opposite sides of said element and a loop member removably secured to said lugs and co-operating with said boiler tube to surround the blower element, the arrangement being such that upon removal of said loop member from said lugs the element may be moved from adjacent said boiler tube.
